GAS PRODUCER AND OTHER FURNACES

Albert Leet Galusha, Caldwell, N. J.

Original application July 17, 1930, Serial No. 468,634. Divided and this application April 24, 1933, Serial No. 667,751

3 Claims. (Cl. 122—5)

This invention deals with the construction of the wall for a combustion chamber and with an ash brake mounted on the wall. The invention was made with particular reference to problems 5 arising in gas producer construction but may be used in furnaces of other sorts or wherever conditions demand or warrant it. One purpose is to eliminate the need of a brick lining on the interior of the combustion chamber wall and to 10 make possible a water-jacketed metal wall that will not cause the fire bed to be cooled to the extent of preventing complete combustion near the wall but nevertheless will itself be kept below a temperature that would cause it to melt.

15 In the drawings—

Fig. 1 is a view in central vertical section through a gas producer in the region of the grate, showing the grate with stirrer arms, the water-jacketed wall and the ash brakes, the construction 20 of the wall illustrating one modification of this invention;

Fig. 2 is a top plan view of the part of a producer shown in Fig. 1, the wall being of the usual construction;

25 Fig. 3 is a detail view in section through the water-jacketed wall, showing the construction of the latter and of the ash brake mounted thereon, drawn to a larger scale;

Fig. 4 is a view in section on the line 4—4 of 30 Fig. 3;

Fig. 5 is a view in vertical section of an alternative form of wall construction.

In the drawings the invention is shown applied to a gas producer of the type shown in my co-pending application Serial No. 468,635, filed July 35 17, 1930. In the type of gas producer there shown two spaced annular shells 10, 11, (Fig. 2), form the wall, providing a water chamber between them. Ordinarily such shells are designed for

40 strength only and the inner shell 10 is from $\frac{1}{16}$ inch to $\frac{3}{8}$ inch thick. According to the prevailing practice before this, the interior of the inner shell would be lined with fire brick either in the region of combustion only or for the full

45 height of the combustion chamber. But fire bricks lead to the formation of clinkers which become cemented on the wall, thus decreasing the size of the region of combustion and disturbing the uniformity of burning. If, however, the brick

50 lining is omitted, the fire is cooled and combustion is retarded near the wall,—obviously an undesirable condition since more of the fuel burns to dioxide gas instead of monoxide gas which it is desired to make in a gas producer.

55 As a solution of this problem, I add to the heat

resistance of the inner shell in order that the heat transfer through the shell to the water, though sufficient to prevent overheating of the shell, may be retarded enough to keep the fire bed from being undesirably cooled. I may do 55 this in several ways, such as by putting a coating of heat resistant material on the outer side of the inner shell or by adding a supplemental shell close to the inner one, or by making the inner shell several times thicker than is necessary for 60 strength alone, or by adding a number of ribs on the outer side of the inner shell. The result in each case is to increase the resistance, or to decrease the rate of heat transfer, two or three times or more, and that maintains the temperature 65 of the inner side below the fusion point of the metal but above a point at which combustion would be retarded near the wall.

When the effect is gained by using a thicker 70 wall, the thickness is of the order of about one 75 inch and upward, being from $\frac{1}{8}$ inch to $1\frac{1}{2}$ inches or more. The added thickness may be in a supplemental shell 12 (Figure 3) or it may be in an integral oversize shell 10' (Figure 1). The horizontal annular ribs 13 (Figure 5) will 80 give the same result. The ribs 13 may be formed by a plurality of rings or by a continuous spirally wound strip, the rings or spiral strip forming an obstruction to the free circulation of the water 85 of the water jacket adjacent the outer face of the shell 10. The rings or the coils of the strip also tend to retain between them the steam bubbles forming on the shell wall and thus retard the 90 radiation of heat from the shell wall. Only the coils of the strip may circulate freely but heat conduction to the rings or the coils of the strip is retarded by the formation of steam bubbles between the shell 10 and the rings or strip.

The grate is of the construction described in 95 my application Serial No. 294,132 filed July 20, 1928, which resulted in Patent No. 1,891,809, issued December 20, 1932, and therefore is not described in detail.

In making producer gas and in pre-heating the 100 moist air going to the furnace, but a fraction of a pound of steam or its equivalent is needed for each pound of solid fuel gasified.

If a gas producer with a complete water-jacket were used with the ordinary metal water-jacket, 105 the flow of heat to the water would be far in excess of the steam consumption requirements. In order to keep the saturated air temperature correct and the steam production accordingly it would be necessary to employ a large amount of 110

jacket-cooling water far in excess of the steam consumption requirements.

My special wall construction above described greatly reduces the total heat flow per hour to the water in the jacket and by this construction I am enabled to increase the efficiency of the machine and to reduce the production of steam and to reduce the use of water to approximately the amount required for use in the fire to make 10 gas.

The grate, stirrer arms and ash brake arms shown in this application are claimed in my co-pending application Serial No. 468,634, filed July 17, 1930, of which application this application is a division.

I claim—

1. In a furnace, a double wall forming a water jacket around the combustion chamber, the inner wall being a metal shell presenting a smooth surface directly contacting with the fuel bed and comprising metal in the combustion zone in addition to the shell thickness needed for strength for decreasing the rate of heat transfer to maintain the temperature of its inner side above a point at which combustion will be retarded near the wall but below the fusion point of the metal.

2. In a furnace, a double wall forming a water jacket around the combustion chamber, the inner wall being a laminated metal shell presenting a smooth surface directly contacting with the fuel bed and comprising metal in the combustion zone in addition to the shell thickness needed for strength for decreasing the rate of heat transfer to maintain the temperature of its inner side above a point at which combustion will be retarded near the wall but below the fusion point of the metal. 30

3. In a furnace, a double wall forming a water jacket around the combustion chamber, the inner wall being a metal shell directly contacting with the fuel bed and comprising closely adjacent substantially horizontal metallic ribs substantially covering the outer face of said inner wall in the combustion zone, in addition to the shell thickness needed for strength for decreasing the rate of heat transfer to maintain the temperature of its inner side above a point at which combustion will be retarded near the wall but below the fusion point of the metal. 35 90 95
